(57) CLAIM

The ornamental design for whitening product package with surface indicia, as shown and described.

DESCRIPTION

FIG. 1 is a front view of a whitening product package with surface indicia showing our new design;

FIG. 2 is a perspective view of a whitening product package with surface indicia showing our new design.

FIG. 3 is identical to FIG. 1 in that it is a front view of a whitening product package with surface indicia showing our new design.

FIG. 4 is a right side view of a whitening product package with surface indicia showing our new design.

FIG. 5 is a left side view of a whitening product package with surface indicia showing our new design.

FIG. 6 is a rear view of a whitening product package with surface indicia showing our new design.

FIG. 7 is a top view of a whitening product package with surface indicia showing our new design; and,

FIG. 8 is a bottom view of a whitening product package with surface indicia showing our new design.

The broken lines shown depict environmental subject matter only and form no part of the claimed design.
